(51) **LOC (9) Cl. 16-01**

(57) **CLAIM**

(52) **U.S. Cl. D16/202; D16/206**

We claim the ornamental design for an LCD monitor equipped video camera using semiconductor memory card, as shown and described.

(58) **Field of Classification Search D16/200,**

DESCRIPTION

D16/202, 203, 204, 205, 206, 208, 218; 348/333.06,
348/373–376; 396/535–541

See application file for complete search history.
